AUTOMATIC FEEDER FOR WASHING MACHINES

William O. Manley, North Kansas City, Mo., assignor to Bill Glover, Incorporated, Kansas City, Mo., a corporation of Missouri

Application January 13, 1954, Serial No. 403,789

6 Claims. (Cl. 222—117)

This invention relates to improvements in machines for washing clothes and particularly to an improved feeder for automatically dumping soap, bluing and the like into the machine in timed sequence during the operation of the machine and without operator attention after the feeder has been conditioned for automatic operation.

It is the most important object of the present invention to provide a feeder for automatic washing machines that includes a plurality of containers swingably mounted for movement to and from a position dumping the contents thereof into the machine, each of which containers is provided with a novel cam-actuated latch normally hooked over a finger on the container.

Another important object hereof is to provide mechanism in a feeder of the aforementioned character for automatically operating the cams in timed sequence to successively release the latches and thereby the containers for swinging movement to a dumping position.

Other objects include the way in which a reciprocable solenoid is provided to impart step-by-step movement to the cam shaft; the way in which the said shaft is provided with ratchet mechanism that includes a pronged wheel actuated by a pawl operably connected with the reciprocable core of the said solenoid; and many other important objects including details of construction, all of which will be made clear as the following specification progresses.

In the drawing:

Figure 1 is a top plan view of an automatic feeder for washing machines made pursuant to the present invention showing one of the containers in a dumped position and the remaining containers held in an upright position by their latches.

Fig. 2 is an end elevational view of the feeder, parts being broken away and in section to reveal details of construction.

Fig. 3 is a fragmentary, elevational view showing the opposite end of the feeder; and

Fig. 4 is a fragmentary, detailed view illustrating the means employed to prevent retrograde rotation of the cam shaft.

Those skilled in the field of automatic machines for washing clothing are well aware of the fact that the provision of an automatic feeder therefor is extremely advantageous because of the time that is saved in eliminating periodic dumping of soaps, bluing and other materials into the washing machine as it completes each step of its cycle of operation.

It is contemplated that the feeder about to be described shall be synchronized with the operation of the automatic washing machine so that the substances aforementioned, will be dumped thereinto in timed sequence, an automatic washing machine being shown in Figs. 1 and 2 of the drawing for illustrative purposes and designated by the numeral 10. In accordance with the present invention there is provided an open top hopper broadly designated by the numeral 12, rigidly secured to the machine 10 through the medium of suitable fasteners 14 and having an outlet

opening 16 communicating directly with the machine 10. Hopper 12 is provided with a pair of end walls 18 and 20 that mount a rod 22, a shaft 24 and a pin 26 in parallelism, the shaft 24 being rotatable on its horizontal axis.

A plurality of containers 28, such as glass jars, are removably mounted on the rod 22 through the medium of frames 30, removably clamped thereto. Each frame 30 is in turn provided with a U-shaped bracket 32 rigid to the bottom thereof and having each of the legs thereof formed in the shape of a hook 34 that is rotatable on the rod 22. Each container 28 is provided with a cap 36 having a restricted opening 38 therein so that the contents of the containers 28 will not flow too rapidly into the hopper 12 and thence into the machine 10 when the containers 28 are permitted to swing to the dumping position resting upon resilient stops 40 mounted on the bottom of hopper 12.

Each of the frames 30 is provided with a rearwardly extending finger 42 on the bottom thereof adjacent the brackets 32 that cooperate with latches 44 when the latter are hooked over the fingers 42 in releasably holding the containers 28 in the upright position. There is a latch 44 for each container 28 respectively, and latches 44 are carried by the pin 26 for swinging movement toward and away from the shaft 24.

A cam member 46 is provided for each latch 44 respectively, the cam members 46 being rigid to the shaft 24 for rotation therewith and the latches 44 being yieldably biased in engagement with their cam members 46 by springs 48 mounted on the hopper 12. It is to be preferred that both the latches 44 and the cam members 46 be adjustable on the pin 26 and shaft 24 respectively, and by spirally offsetting the cam members 46 throughout the length of the shaft 24, the containers 28 will be released sequentially as the shaft 24 is rotated in one direction, i.e., clockwise viewing Fig. 3.

Step-by-step rotation of the shaft 24 is attained through use of a solenoid 50 mounted on the wall 18 and having a reciprocable core 52 to which is pivotally secured a pawl 54. Pawl 54 is yieldably biased in one direction by a spring 56 connecting the same with wall 18 and is provided with a lateral stud 58 engageable with the prongs of a star wheel 60. Retrograde rotation of the shaft 24 anti-clockwise, viewing Fig. 4, is prevented by use of another ratchet 62 rigid to the shaft 24, together with a spring 64 engageable therewith. The shaft 24 may be rotated manually to set the cams 46 by a knob 66 rigid to that end of shaft 24 opposite to the two ratchets or wheels 60 and 62.

In operation, the containers 28 may be filled with predetermined amounts of material to be fed by removing caps 36 and this filling operation may take place by removing the entire frames 30 and the containers 28 from the rod 22.

The containers 28 and frames 30 are thereupon remounted on the rod 22 in the upright position with the latches 44 in hooked relationship to the fingers 42 as is clear in Fig. 2.

During operation of the machine 10 through use of its timing mechanism (not shown) the solenoid 50 is operated to impart step-by-step rotation to the shaft 24 and thereby successively trip the latches 44 through the cams 46. The order of dumping of the contents of the containers 28 is determined by the relative positions of the cams 46 on the shaft 24 and it may now be appreciated that any number or all of the containers 28, may be utilized as desired by the operator. Shaft 24 may be rotated manually through use of the knob 66 to correctly position the cams 46 for the operation desired.

Each time the solenoid 50 is energized, a pull is exerted upon the pawl 54 against the action of spring 56 and the

pin 58 will rotate the ratchet wheel 60 in one direction by engagement with the prongs thereof.

The way in which selected containers 28 may be used; the manner of adjusting the sequence of dumping thereof; and the manner of connecting the power means 50 with the shaft 24 so as to permit independent rotation of the shaft 24 through use of the knob 66, are all important features of the present invention and while details of construction may be varied within the spirit of the invention, it is desired to be limited only by the scope of the appended claims.

Having thus described the invention what is claimed as new and desired to be secured by Letters Patent is:

1. In a washing machine having a hopper, a support, and a plurality of containers swingably mounted on the support for gravitational movement to a position dumping their contents into the hopper; a finger for each container respectively; a swingable latch for each finger respectively and engageable therewith for holding the containers against swinging movement to said position; a rotatable shaft; a cam member for each latch respectively and rigid to the shaft, said cam members having cam surfaces disposed to engage their latches to swing the same out of engagement with the fingers upon rotation of the shaft; and structure operably coupled with the shaft for imparting rotation thereto.

2. In a washing machine having a hopper, a support, and a plurality of containers swingably mounted on the support for gravitational movement to a position dumping their contents into the hopper; a finger for each container respectively; a swingable latch for each finger respectively and engageable therewith for holding the containers against swinging movement to said position; a rotatable shaft; a cam member for each latch respectively and rigid to the shaft, said cam members having cam surfaces disposed to engage their latches to swing the same out of engagement with the fingers upon rotation of the shaft, said cam members having their cam surfaces spirally offset relatively along the shaft whereby the latches are successively tripped and the containers thereby successively dumped as the shaft is rotated; and structure operably coupled with the shaft for imparting rotation thereto.

3. In a washing machine having a hopper, a support, and a plurality of containers swingably mounted on the support for gravitational movement to a position dumping their contents into the hopper; a finger for each container respectively; a swingable latch for each finger respectively and engageable therewith for holding the containers against swinging movement to said position; a rotatable shaft; a cam member for each latch respec-

tively and rigid to the shaft, said cam members having cam surfaces disposed to engage their latches to swing the same out of engagement with the fingers upon rotation of the shaft; springs bearing against the latches for yieldably holding the same biased against the cam members; and structure operably coupled with the shaft imparting rotation thereto.

4. In a washing machine having a hopper, a support, and a plurality of container swingably mounted on the support for gravitational movement to a position dumping their contents into the hopper; a finger for each container respectively; a swingable latch for each finger respectively and engageable therewith for holding the containers against swinging movement to said position; a rotatable shaft; a cam member for each latch respectively and rigid to the shaft, said cam members having cam surfaces disposed to engage their latches to swing the same out of engagement with the fingers upon rotation of the shaft; and structure for rotating the shaft including ratchet mechanism having a pronged wheel mounted on the shaft, a reciprocable pawl provided with a pin engageable with the prongs of said wheel to rotate the wheel, and a solenoid having a reciprocable core connected with the pawl to reciprocate the latter.

5. In a washing machine as set forth in claim 4 wherein is provided a manually manipulable knob on said shaft for rotating the latter to position the cam members, said shaft and said wheel being rotatable in one direction relative to the pawl.

6. In a washing machine having a hopper, a support, and a plurality of containers swingably mounted on the support for gravitational movement to a position dumping their contents into the hopper; a finger for each container respectively; a swingable latch for each finger respectively and engageable therewith for holding the containers against swinging movement to said position; a rotatable shaft; a cam member for each latch respectively; means releasably mounting each cam member on the shaft, each cam member having a cam surface disposed to engage and trip the corresponding latch and being rotatable on the shaft when the mounting means therefor is released; and structure operably coupled with the shaft for imparting rotation thereto and to the members whereby to dump the containers sequentially according to the radial disposition of said surfaces.
